COMBINED WALL TYPE SAFETY RAZOR AND BLADES HOLDER

Joseph D. Cudd, Boise, Idaho

Application April 3, 1957, Serial No. 45,571

Term of patent 14 years

(Cl. D4—3)

Figure 1 is a front elevational view of a combined wall type safety razor and blades holder, showing my new design.

Figure 2 is a left side elevational view.

Figure 3 is a right side elevational view.

Figure 4 is a rear elevational view.

Figure 5 is an end elevational view.

The safety razor and package of blades indicated in phantom in Figure 1 are depicted for illustrative purposes only.

I claim:

The ornamental design for a combined wall type safety razor and blades holder, as shown and described.
